PNEUMATIC ROLL CHUCK

William F. Collard, Sr., Camas, Wash., and Lewis L. Collard, deceased, late of Camas, Wash., by William F. Collard, administrator

Application April 13, 1953, Serial No. 348,528

12 Claims. (Cl. 242—72)

The present invention relates in general to improvements in devices for facilitating rotation of rolls of sheet material such as paper, and relates more specifically to improvements in the construction and operation of pneumatic roll driving chucks especially useful for effecting unwinding of paper rolls or the like.

The primary object of the present invention is to provide a pneumatic roll driving chuck which is simple and compact in construction and highly efficient in operation.

It is common practice in the paper making industry, to wind the finished paper stock on relatively heavy cardboard cores or tubes which become a permanent part of the final paper rolls. While some mills have heretofore resorted to the use of removable metal cores instead of cardboard tubes, the latter are relatively inexpensive and besides effectively protecting the inner layers of the rolled stock, they may be utilized to greatly facilitate unwinding of the rolls if a suitable drive for rotating the cores is provided.

It is therefore an important object of this invention to provide an improved chuck especially adapted for the purpose of unwinding rolls of paper or the like, and which may be conveniently applied to such rolls and used to effectively rotate the same in either direction.

Another important object of the invention is to provide a roll chuck readily applicable to either end of a hollow roll, and which is pneumatically operable to either establish or to release the driving connection between the roll and a source of power.

A further important object of the present invention is to provide an improved pneumatic roll chuck having two sets of jaws operable by a common inflatable element to drivingly connect a roll to a rotary shaft disposed coaxially of the roll.

Still another important object of this invention is to provide a compact and relatively inexpensive chuck for drivingly connecting a roll to a driving shaft extending centrally through the roll, which may be easily applied or removed and functions to effectively drive the roll at will.

An additional object of the invention is to provide a durable roll driving chuck for hollow rolls of various types, which comprises relatively few sturdy parts adapted to accurately centralize the rolls relative to their supporting and driving shaft and to produce an effective driving connection.

These and other more specific objects and advantages of the invention will be apparent from the following detailed description from which it will be noted that the gist of the present improvement is the provision of a chuck for drivingly connecting a rotary shaft with a hollow roll of paper or the like, with the aid of inner and outer revolving jaws adapted to be simultaneously spread apart by means of an inflatable element so as to cause the inner jaws to grip the shaft while also causing the outer jaws to grip the interior of the roll, and wherein the driving connection is interrupted whenever the element is deflated.

A clear conception of the features constituting the present improvement and of the construction and operation of a typical roll driving chuck embodying the invention, may be had by referring to the drawing accompanying and forming a part of this specification wherein like reference characters designate the same or similar parts in the two views.

Fig. 1 is an approximately central longitudinal section

through a commercial pneumatic roll chuck taken along the line 1—1 of Fig. 2, showing the same applied to fragments of a driving shaft and of a hollow paper roll surrounding the shaft; and

5 Fig. 2 is a partial end view and transverse section through the chuck, the section having been taken along the line 2—2 of Fig. 1, and the roll being omitted.

While the improved chuck illustrated and described herein embodies inner and outer sets of gripping jaws each comprising three individual jaws adapted to grip the driving shaft and the interior of a paper roll core near its extreme end, it is not the intent to unnecessarily restrict the invention by virtue of this limited embodiment; and it is also contemplated that specific descriptive terms employed herein be given the broadest possible interpretation consistent with the disclosure.

Referring to the drawing, the improved pneumatic roll chuck shown therein is adapted to drivingly connect the tubular core 4 of a roll 5 of paper or the like, with a rotary driving member or shaft 6 disposed coaxially of the hollow roll 5; and the chuck comprises an annular support 7 loosely surrounding the shaft 6; a set of three inner shaft gripping jaws 8 slidably associated with the support 7; a set of three outer core gripping jaws 9 pivotally suspended from the support 7; and an annular expandible element or cylindrical bag 10 interposed between the jaws 8, 9 and being inflatable to simultaneously force the inner jaws 8 into driving engagement with the shaft 6 and the outer jaws into driving engagement with the interior of the core 4.

20 The annular support 7 has a cylindrical externally smooth housing or casing 12 firmly but removably attached to one end thereof by means of cap screws 13 so that the casing in effect constitutes a part of the support, and the opposite end of the support 7 is provided with an integral annular flange having thereon integral suspension ears 14 carrying pivot pins 15 from which the outer jaws 9 are radially swingably suspended, while the medial portion of the support 7 has elongated radial slots 16 formed therein for slidably mounting the inner jaws 8. The end wall of the casing 12 remote from the pivot pins 15 is also provided with integral external parallel guideways 17 for the swinging ends of the outer jaws 9, and has an inner guard plate 18 secured thereto by screws 19.

25 Each of the three inner jaws 8 lies loosely within and is freely radially movable or slidable in one of the slots 16 of the unitary support 7, and is provided at its outer portion with oppositely directed integral arcuate flanges 21 which cooperate with the arcuate flanges of the adjacent jaws 8 to provide substantially a complete hollow cylinder surrounding the inner hub portion of the support 7 and this hub portion is provided with radial sockets 22 facing the inner jaw flanges 21. A helical compression spring 23 is confined within each of the sockets 22 and presses outwardly against the adjacent flange 21, thereby constantly urging the adjacent jaw 8 radially away from the periphery of the driving shaft 6, and the flanges 21 also serve to retain the springs 23 confined within the sockets 22.

30 Each of the three outer jaws 9 is provided at its pivoted end with an integral suspension lug 25 coacting with the adjacent pivot pin 15 between its carrying ears 14, while its opposite swinging end has arcuate externally serrated gripping extensions 26 formed integral with long inwardly projecting flat guiding portions 27 slidably coacting with the guideways 17 of the casing 12, and the portion of each jaw 9 between the lug 25 and its guiding portion 27 is provided with oppositely directed integral arcuate flanges 28 which cooperate to provide a substantially complete hollow cylinder surrounding the bag 10. The end wall of the casing 12 on which the guideways 17 are formed, is also provided with radial sockets 29 on opposite sides of stop screws 30 and which face the swinging medial portions 31 of the jaws 9 located between the flanges 28 and the guiding portions 27.

35 A helical compression spring 32 is confined within each of the sockets 29 and pressed inwardly against the adjacent jaw portion 31, thereby constantly urging the outer jaw gripping extensions 26 toward the shaft 6, and the springs 32 are confined within their

sockets 29 by the jaw portions 31 and by screw plugs 33 secured to the casing end wall.

The annular expandable element or bag 10 which is confined between the flanges 21, 28 of the inner and outer jaws 8, 9, is preferably formed of material such as rubber, and surrounds and extends throughout the entire length of the slotted portion of the support 7. The interior of the bag 10 is provided with a normally sealed and unobstructed annular chamber 35, and the bag 10 has a single inlet and outlet opening 36 at one end with which a valve assemblage 37 is associated. This valve assemblage 37 is somewhat similar to an automobile tire valve, and comprises a body 38 having a seat 39 formed therein, and a valve 40 constantly urged toward the seat 39 by a helical spring 41 so as to normally seal the chamber 35 of the bag 10. This construction permits the valve 40 to be opened either by the admission of fluid under pressure such as compressed air through the body 38 in order to inflate the bag 10, or by manually pressing the valve away from its seat so as to permit fluid to escape from the chamber 35.

When the various parts of the improved pneumatic roll chuck have been properly constructed as above described, they may be readily assembled as shown, by merely manipulating the screws 13, 19 and the pins 15 and plugs 33, so as to maintain the springs 23, 32 and other elements of the unit in proper position. The assembled unit may then be applied axially to a driving shaft 6 while at rest, whereupon the outer jaw extensions 26 may be slipped into the end of a roll core 4 surrounding the shaft 6 until the jaw portions 27 engage the end of the roll 5, so as to hold the roll in approximate axial alignment with the driving shaft.

After the chuck unit has been thus applied to the shaft 6 and roll 5, the stop screws 30 should be adjusted to limit and equalize the outward swinging motion of the jaws 9 and their extensions 26, whereupon fluid under pressure such as compressed air, may be admitted to the chamber 35 of the annular bag 10 through the valve assemblage 37 and opening 36. The bag 10 will then expand and will simultaneously force the three inner jaws 8 radially within the slots 16 into firm frictional engagement with the shaft 6 and the three outer jaw extensions 26 into driving engagement with the interior of the roll core 4. When a cardboard core 4 is provided, the teeth or serrations of the outer jaw extensions 26 will bite into the relatively soft core 4 and will thus provide a positive drive for the roll 5 while also centralizing this roll relative to the shaft 6. The shaft 6 may thereafter be rotated to revolve the roll 5 in the proper direction so that paper may be unwound therefrom or additional stock may be wound thereon, and the improved chuck units may be applied to either or both ends of the rolls 5.

In order to release the improved chuck from a roll core 4, it is only necessary to stop the driving shaft 6 and to press the valve 40 away from its seat 39 with the aid of any blunt ended implement. When the valve 40 is thus unseated, the compression springs 23 quickly become effective to spread the inner jaws 8 radially within their confining slots away from the shaft periphery, and the compression springs 32 likewise act to simultaneously move the outer jaws 9 and their extensions 26 toward the shaft sufficiently to release the roll core 4. The core 4 may then be slid longitudinally off of the extensions 26 and a new roll may be applied in like manner, and the peripherally smooth annular casing 12 normally conceals most of the mechanism and thus protects attendants from injury while the chuck is in use.

From the foregoing detailed description it will be apparent that the present invention in fact provides a simple and extremely compact and durable roll driving chuck unit which may be conveniently applied to and removed from the ends of paper rolls 5 or the like, and which is adapted to effectively rotate the rolls for unwinding or rewinding purposes. The pneumatic bag 10 cooperates with the arcuate jaw flanges 21, 28 to quickly establish a firm driving connection between the shaft 6 and the roll 5 whenever the bag is inflated, and the springs 23, 32 function to likewise interrupt the driving connection when the bag 10 is opened to the ambient atmosphere. The improved unit may be readily assembled or dismantled by merely manipulating a few screws and pins, and the assemblage may be operated with utmost safety due to the smooth external surfacing of the annular casing 12 which also protects the internal mechanism from damage. The

improved chucks have gone into extensive and highly successful commercial use, and may be manufactured in various sizes for diverse uses.

It should be understood that it is not desired to limit this invention to the exact details of construction and operation of the pneumatic roll chuck herein specifically shown and described, for various modifications within the scope of the appended claims may occur to persons skilled in the art.

10 We claim:

1. In a chuck for drivingly connecting a rotary shaft with a hollow roll, a support surrounding the shaft, inner jaws movably associated with said support and being engageable with said shaft to drivingly connect the support to the shaft, outer jaws movably suspended from said support and being engageable with the interior of said roll to drivingly connect the roll to the support, and an inflatable element for simultaneously moving said jaws into driving engagement with said shaft and with said roll whenever the element is inflated.

15 2. In a chuck for drivingly connecting a rotary shaft with a hollow roll, a support surrounding the shaft, inner jaws movably associated with said support and being engageable with said shaft to drivingly connect the support to the shaft, outer jaws movably suspended from said support and being engageable with the interior of said roll to drivingly connect the roll to the support, an inflatable element for simultaneously moving said jaws into driving engagement with said shaft and with said roll whenever the element is inflated, and resilient means coacting with said support and with said jaws for releasing the latter when said element is deflated.

20 3. In a chuck for drivingly connecting a rotary shaft with a hollow roll disposed coaxially of the shaft, a support surrounding the shaft, inner jaws slidably associated with said support and being inwardly movable into engagement with said shaft to drivingly connect the support to the shaft, outer jaws pivotally suspended from said support and being outwardly swingable into engagement with the interior of said roll to drivingly connect the roll to the support, and an inflatable element for simultaneously moving said jaws into driving engagement with said shaft and with said roll whenever the element is inflated.

25 4. In a chuck for drivingly connecting a rotary shaft with a hollow roll disposed coaxially of the shaft, a support surrounding the shaft, inner jaws slidably associated with said support and being inwardly movable into engagement with said shaft to drivingly connect the support to the shaft, outer jaws pivotally suspended from said support and being outwardly swingable into engagement with the interior of said roll to drivingly connect the roll to the support, an inflatable element for simultaneously moving said jaws into driving engagement with said shaft and with said roll whenever the element is inflated, and springs coacting with said support and with said jaws for releasing the latter when said element is deflated.

30 5. In a chuck for drivingly connecting a rotary shaft with a hollow roll, a support surrounding the shaft and having radial slots and guideways therein, an inner jaw radially slidable within each of said slots and being engageable with said shaft to drivingly connect the support to the shaft, an outer jaw radially slidably coacting with each of said guideways and being engageable with the interior of said roll to drivingly connect the roll to the support, and an inflatable element for simultaneously moving all of said jaws into driving engagement with said shaft and with said roll whenever the element is inflated.

35 6. In a chuck for drivingly connecting a rotary shaft with a hollow roll, a support surrounding the shaft and having radial slots and guideways therein, inner jaws slidable radially within said slots and being engageable with said shaft to drivingly connect the support to the shaft, outer jaws slidably within said guideways and being engageable with the interior of said roll to drivingly connect the roll to the support, an inflatable element for simultaneously moving said jaws into driving engagement with said shaft and with said roll whenever the element is inflated, and resilient means coacting with said support and with said jaws for releasing the latter when said element is deflated.

40 7. In a chuck for drivingly connecting a rotary shaft with a hollow roll, a rigid annular support having

radial slots and intervening radial guideways therein, inner jaws radially slidably confined within said slots and being engageable with said shaft to drivingly connect the support to the shaft, outer jaws radially slidably confined within said guideways and being engageable with said roll to drivingly connect the roll to the support, and an inflatable annular element disposed between the jaws for simultaneously moving said jaws into driving engagement with said shaft and with said roll whenever the element is inflated.

8. In a chuck for drivingly connecting a rotary shaft with a hollow roll, a rigid annular support having radial slots and intervening radial guideways therein, inner jaws radially movably confined within said slots and being engageable with the periphery of said shaft to drivingly connect the support to the shaft, outer jaws radially movably confined within said guideways and being engageable with the interior of said roll to drivingly connect the roll to the support, an annular inflatable element interposed between the jaws for simultaneously moving said jaws into driving engagement with said shaft and with said roll whenever the element is inflated, and resilient means carried by said support and coacting with said jaws for releasing the latter when said element is deflated.

9. In a chuck for drivingly connecting a rotary shaft with a hollow roll disposed coaxially of the shaft, a support surrounding the shaft, inner jaws slidably associated with said support and being inwardly movable into engagement with said shaft to drivingly connect the support to the shaft, outer jaws pivotally suspended from said support and being outwardly swingable into engagement with the interior of said roll to drivingly connect the roll to the support, each of said jaws having arcuate flanges thereon cooperating to form inner and outer hollow cylinders, and an inflatable element interposed between said cylinders for simultaneously moving said jaws into driving engagement with said shaft and with said roll whenever the element is inflated.

10. In a chuck for drivingly connecting a rotary shaft with a hollow roll disposed coaxially of the shaft, a support surrounding the shaft and having radial slots and intervening radial guideways formed therein, inner jaws slidably confined within said slots and being inwardly movable into engagement with said shaft to drivingly connect the support to the shaft, outer jaws slidably confined within said guideways and being outwardly swingable into engagement with the interior of

said roll to drivingly connect the roll to the support, said jaws having arcuate flanges thereon forming inner and outer hollow cylinders, and an inflatable element between and coacting with said flanges to simultaneously move said jaws into driving engagement with said shaft and with said roll whenever the element is inflated.

11. In a chuck for drivingly connecting a rotary shaft with a hollow roll disposed coaxially of the shaft, a support surrounding the shaft and having rigid slots and intervening guideways therein, inner jaws slidably engaging said slots and being inwardly movable into engagement with said shaft to drivingly connect the support to the shaft, outer jaws pivotally suspended from said support and being outwardly movable along said guideways into engagement with the interior of said roll to drivingly connect the roll to the support, each of said jaws having a pair of oppositely directed arcuate flanges thereon forming inner and outer hollow cylinders, an inflatable annular bag interposed between said cylinders for moving said jaws into driving engagement with said shaft and with said roll whenever the element is inflated, and springs coacting with said support and with said jaw flanges for releasing the latter when said element is deflated.

12. In a chuck for drivingly connecting a rotary shaft with a hollow roll disposed coaxially of the shaft, a rigid support surrounding the shaft, inner jaws slidably associated with said support and being inwardly movable into engagement with said shaft to drivingly connect the support to the shaft, outer jaws pivotally suspended from said support and being outwardly swingable into engagement with the interior of said roll to drivingly connect the roll to the support, each of said jaws having oppositely directed arcuate flanges cooperating to form inner and outer concentric hollow cylinders, an inflatable annular rubber bag interposed between said cylinders for moving said jaws into driving engagement with said shaft and with said roll whenever the element is inflated, and springs coacting with said support and with said flanges for releasing the latter when said element is deflated.
